(57) **CLAIM**

The ornamental design for an axe blade cover, as shown and described.

DESCRIPTION

FIG. 1 is a perspective view of an axe blade cover according to our new design;

FIG. 2 is a perspective view of the axe blade cover, wherein the components are dissembled;

FIG. 3 is a left-side elevation view of our axe blade cover;

FIG. 4 is a right-side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a side-perspective view thereof; and,

FIG. 10 is a side-perspective view of the axe blade cover, wherein the components are dissembled.
